The ornamental design for the controller for weight sensing pad, as shown and described.

DESCRIPTION

FIG. 1 is a perspective of the controller for weight sensing pad;

FIG. 2 is a top plan view of the controller for weight sensing pad shown in FIG. 1;

FIG. 3 is a bottom view of the controller for weight sensing pad shown in FIG. 1;

FIG. 4 is a first side view of the controller for weight sensing pad shown in FIG. 1;

FIG. 5 is a second side view of the controller for weight sensing pad shown in FIG. 1;

FIG. 6 is an elevational first end view of the controller for weight sensing pad shown in FIG. 1; and,

FIG. 7 is an elevational second end view of the controller for weight sensing pad shown in FIG. 1.

The broken line showing of structural features is included for the purpose of illustrating non-claimed subject matter and forms no part of the claimed design.
